Primary Examiner — Mark A Goodwin(74) *Attorney, Agent, or Firm* — Bretton L. Crockett;
TechLaw Ventures, PLLC(57) **CLAIM**

The ornamental design for a liquid storage vessel, as shown and described.

DESCRIPTION

FIG. 1 a perspective view of a liquid storage vessel,
 FIG. 2 is a top view of the liquid storage vessel,
 FIG. 3 is a front view of the liquid storage vessel; and,
 FIG. 4 is a left side view of the liquid storage vessel.
 The indicia depicted by means of broken lines in the
 drawings are shown for illustrative purposes only and form
 no part of the claimed design.
